United States Patent Office

Des. 192,297

Patented Feb. 27, 1962

192,297

FEEDING DISH

Avis M. Klier, Wheatland, Wyo.

Filed Feb. 27, 1958, Ser. No. 49,835

Term of patent 14 years

(Cl. D44—15)

FIG. 1.

FIG. 2.

I claim:

The ornamental design of a feeding dish, as shown.
